UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,131, dated September 29, 1896.

Application filed August 24, 1896. Serial No. 603,789. Term of patent 31 years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of an arrangement of large fleur-de-lis-shaped ornaments with light lines diverging right and left from said ornaments and forming connecting panels, with ornamental scrolls in said panels, as represented in the accompanying drawing.

The border for the said design is also formed of similar large fleur-de-lis-shaped ornaments with ornamental scrolls diverging right and left from the base of said ornaments and small ornamental figures at the intersection of said scrolls, as shown in the drawing.

What I claim is—

1. The design for wall-paper herein shown and described.
2. In the design for wall-paper the border herein shown and described.

Witness my hand this 10th day of August, 1896.

CHARLES BOOZ.
